UNITED STATES PATENT OFFICE.

HENRY D. SMITH, OF LOS ANGELES, CALIFORNIA.

FOLDING TABLE.

Application filed March 23, 1926. Serial No. 96,695.

This invention is a folding table for use by campers and the like; and it is the object of the invention to fold the table into a compact box-like receptacle carrying all parts of the table and forming a container for cooking and eating utensils or other camping equipment, and adapted for convenient transportation on the running board of a vehicle.

10 It is a further object of the invention to provide a table which may be quickly set up for use without the need of tools, and which when in operative position may form either a combined table and benches, or comfortable camp chairs.

15 It is a still further object of the invention to provide an extremely sturdy but simple construction which will form rigid and substantial camping furniture adapted to safely 20 carry any weight to which it may be subjected in the ordinary course of use as camping equipment.

The invention will be readily understood from the following description of the accompanying drawings, in which:

25 Fig. 1 is a perspective view showing the table in use.

Fig. 2 is a similar view showing use of the construction as camp chairs.

30 Fig. 3 is a perspective view of the device in folded position.

Figs. 4 and 5 are transverse sections on the lines 4-4 and 5-5 of Fig. 1.

35 The improved construction comprises a box-like receptacle having ends 1 connected by top and bottom 2 and 3 which extend the width of the receptacle, and having the lower portions of the sides of the end pieces connected by side pieces 4 so as to leave the 40 receptacle open between the upper edges of the side pieces and the underside of the top.

The top 2 is of a size to form the center panel of a table, and leaves 5 are hinged at 45 to the respective side edges of top 2, so that they may either extend outwardly in the plane of the top and complete the table as shown in Fig. 1, or may swing downwardly against the receptacle to close the openings above side pieces 4 as shown in Fig. 3.

50 In order to releasably fix the leaves 5 in their extended position, a bar 7 extends the length of the receptacle medially of the underside of top 2, and said bar is cut away at its central portion to receive a brace 8 which 55 is pivoted at its center on pin 9 so that the brace may either lie within the bar 7 or be

swung transversely of the receptacle to project beyond opposite sides of top 2 and thereby form a support for the folding table leaves.

60 The legs of the table are shown at 10, and are removably projected through guide loops 11 on the inner surfaces of end pieces 1 and at the respective sides of bar 7, so that the upper ends of the legs which are 65 cut to the proper angle as shown at 12, will fit snugly in the angles formed by the sides of bar 7 and the underside of top 2, with said ends of the legs preferably guided in 70 channels formed by strips 13 on the sides of bar 7 in slightly spaced relation from the ends 1.

75 The lower ends of the legs will thus project beyond the sides of the table at its respective ends to form a sturdy and rigid construction, and the legs are preferably braced by bars 14 detachably connecting the legs at each end of the table. Each bar 14 is pivoted to the insides of a leg at one side of the table as shown at 15, so that the 80 bar may be swung across to the leg at the opposite side of the table for detachable connection thereto by a bayonet slot 16 in the swinging end of the brace adapted to engage a stud 17 which projects from the insides of said opposite table leg.

85 The brace bars are so positioned that when in use they will lie in grooves 18 extending across the bottom 3 in order to brace the construction longitudinally as well as transversely; and in order that the brace bars will not cause excessive wear of the walls of the grooves, protector plates 19 may be fixed around the ends of the grooves with ears 20 of said plates bent to extend along the 95 sides of the grooves.

90 Benches for the table are mounted on the transversely projecting legs 10, and for this purpose brackets 25 are fixed on the respective legs so that seat boards 26 may have 100 their ends supported on the longitudinally spaced brackets at each side of the table. The seat boards are preferably shiftable toward and away from the table for convenience in seating and use of the table, and as 105 an instance of this arrangement channel pieces 27 are slidable along the horizontal arms of brackets 25, with the ends of the seat boards mounted on said channel pieces. The ends of the seat boards are detachably 110 fixed to the channel pieces, as for example by pins 28 projecting from the underside of

the ends of the boards adjacent the respective sides thereof and adapted to be received in cooperating recesses 29 provided in suitable strips 30 which are fixed on the channel pieces.

The entire table may thus be assembled without the use of tools, and forms a rigid construction with benches at the sides of the table and a tray formed by bottom 3 beneath the table and readily accessible through the openings above the side pieces 4.

When it is desired to use the device as camp chairs rather than a table, brace 8 is swung back into the recess in bar 7 so that the leaves 5 may be folded down against the legs 10; and the angular disposition of the legs fixes the folded leaves at a rearward inclination as shown in Fig. 2 so that the leaves provide comfortable backs for the seat boards 26. Camp chairs are thus formed at each side of the top 2, which latter may still be used as a small table for articles which it is desired to have conveniently at hand.

When the entire device is to be folded for transportation, the seat boards 26 are removed from the channel pieces 27, and the bayonet slot connections 16-17 are released so that the braces 14 may be folded along the legs to which they are pivoted, and all of the legs are then removed by withdrawing them from the guide loops 11.

The box-like receptacle forming the main portion of the structure is of a size to conveniently receive the legs 10 and the bench boards 26 and still leave a large space within the receptacle which may be used for storing cooking and eating utensils, etc.; and after the receptacle is packed and the brace 8 is swung to inoperative position within the bar 7, the leaves 5 are swung down to close the sides of the receptacle and are preferably secured by latches 35 on the side pieces 4.

A handle 36 may be provided on the bottom 3 so that the closed receptacle which is thus formed may be conveniently transported and carried on the running board of an automobile or the like; and the folded construction provides not only a self contained table but a sturdy and handy container for other camping equipment.

I claim:

1. A device of the character described comprising a box-like receptacle including a closed base and upwardly projecting side walls partially enclosing the sides of the receptacle to form a storage space, supporting legs projecting from the interior of the receptacle above its partially enclosed sides and adapted for removal and storage in the receptacle, the underside of the base being transversely recessed, and braces engageable

in said transverse recesses and detachably connecting the legs at opposite sides of the receptacle.

2. A device of the character described comprising a box-like receptacle having a closed base and top and sides adapted to swing open, means for releasably supporting the sides in open position in the plane of the top of the receptacle to form a table top, supporting legs removably insertable in operative position in the receptacle through the open sides of the same so as to project outwardly and downwardly from the sides of the receptacle, and seats removably supported on the legs, the sides of the receptacle being adapted to swing downwardly upon release of their supporting means so as to rest against the legs and form backs for the seats, the seats and legs being adapted for storage in the receptacle when transporting the same.

3. A device of the character described comprising a box-like receptacle having sides adapted to swing open, means for releasably supporting the sides in open position in the plane of the top of the receptacle to form a table top, supporting legs projecting outwardly and downwardly from the interior of the receptacle at the sides of the same, and seats on said legs, the sides of the receptacle being adapted to swing downwardly upon release of said supporting means so as to rest against the legs and form backs for the seats.

4. A device of the character described comprising a frame forming a top and having sides adapted to swing upwardly into the plane of the top, supporting legs for the frame, and seats on said legs, the supporting legs projecting outwardly and downwardly from the sides of the frame in position whereby the swinging sides are adapted to swing downwardly so as to rest against the legs and form backs for the seats.

5. A device of the character described comprising a frame forming a top and having sides adapted to swing upwardly into the plane of the top, supporting legs for the frame, brackets on the legs, connecting means shiftable along the brackets for adjustment toward and away from the top, and seats removably mounted on the connecting means, the supporting legs projecting outwardly and downwardly from the sides of the frame in position whereby the swinging sides are adapted to swing downwardly so as to rest against the legs and form backs for the seats.

In testimony whereof I have affixed my signature to this specification.

HENRY D. SMITH.
